UNITED STATES PATENT OFFICE.

THOMAS SUCHLA, OF COURTENAY, NORTH DAKOTA, ASSIGNOR TO JOHN SMIEJA, OF ROYALTON, MINNESOTA.

HAME-CONNECTOR.

1,083,870.

Specification of Letters Patent.

Patented Jan. 6, 1914.

Application filed May 15, 1912. Serial No. 697,501.

To all whom it may concern:

Be it known that I, THOMAS SUCHLA, a citizen of the United States, residing at Courtenay, in the county of Stutsman and State of North Dakota, have invented new and useful Improvements in Hame-Connectors, of which the following is a specification.

This invention relates to hame connectors and the object of the invention is to provide a simple and efficient device whereby the ends of the hames may be rapidly connected and drawn together in proper relation, and whereby the device may be adjusted so as to accommodate the hames to collars of different sizes.

A further object of the invention is to provide a device of this character having a strap and hook connection with the ends of the separate hame members and with means for drawing the ends of the hames together after connection between the ends of the members has been established.

Further objects of this invention will appear as the following specific description is read in connection with the accompanying drawing, which forms a part of this application, and in which:—

Figure 1 is a side elevation of the device shown applied to the ends of a pair of hames and showing in dotted lines the position of the device when disconnected from one end. Fig. 2 is a longitudinal section through the device removed from the hame. Fig. 3 is a bottom plan view of the device in open position.

Referring more particularly to the drawing, 1 and 2 represent the separate ends of the hame members to be connected together. 40 My improved device for connecting the ends consists of an upper member 4 having side flanges 5 and a pair of slots 6 and 7 in its top separated to produce a bridge bar 8 having a depending forwardly extending tongue 9, as shown. The forward end of the device is provided with an inwardly or downwardly turned lug 10 and is apertured at 11 to receive a hook member 12. This hook member is provided with a plurality of slots 13 adapted to engage the lug 10 so that the hook member may be adjusted upon the member 4. This hook member is adapted to

engage one of the strap loops 3, as shown in Fig. 1.

Pivoted to the flanges 5 is the bottom member 14, whose legs are connected together by a bridge piece 16 having an inwardly or upwardly extending tongue 17. This bridge piece is separated from the connecting end by a slot 19 through which the strap 20 is adapted to pass. This strap is engaged with the tongue 17 at one end and with the tongue 9 at the opposite end, being adjustable at both points as will be readily understood. The upper member 4 is provided with an inwardly and rearwardly curled lip 21 over which is adapted to engage an upwardly and rearwardly curled lip 22 carried by the end 18. The lips 21 and 22 are so arranged that the latter will snap over the former and hold the parts firmly in the position shown in Fig. 1.

The hook member 12 is held with the lug 10 in engagement with the apertures 13 thereof by means of the locking pin 23 which passes through an aperture in the lug 10 and has its end seated in the aperture 24 formed in one of the flanges 5. The end of this locking pin is bent to extend around the lug 10 so as to prevent its disengagement therefrom. The device may be attached to one end of the hames by inserting the strap 20 through the loop 3 and then passing the same through the slots 6 and 7 so as to bring the tongue 9 into position to enter one of the apertures in the strap. The hook member 12 is then engaged with the loop on the opposite member and the member 14 moved so as to bring the lip 23 over the lip 21. This will draw the parts of the hames together so that they will be firmly clamped on the collar.

What is claimed is:—

A hame connector comprising a pair of upper and lower members pivoted together at one end and slotted adjacent the free ends thereof, said upper member having a top and side walls, means for removably securing the free ends of the members together, a strap connected to the free end of the lower member and to the pivoted end of the upper member, an upwardly extending tongue formed on the lower member, said upper member having formed integral there-

with at a point adjacent the free end thereof an inwardly extending apertured lug, said lug being disposed substantially in vertical alinement with said tongue, an apertured 5 hame engaging hook extending through the slot of said upper member and adapted to receive said lug, one of the side walls of the upper member having an aperture, and a locking key extending through the lug and

having its free end arranged in the aperture 10 formed in the side wall of said upper member.

In testimony whereof I affix my signature in presence of two witnesses.

THOMAS SUCHLA.
